4 Claims. (Cl. 57—51)

The present invention relates to a device for periodical-
ly pulling carded yarn passing through a drafting arrange-
ment provided with means placed in the drafting field
for applying a false twist to the yarn.

Pulling means combined with false twist applying
means are known through which the movement of the
material to be spun is periodically interrupted. Diversion
of the yarn is effected by horns mounted on the twisting
element. This conventional pulling device cannot be in-
stalled in existing drafting arrangements wherein the yarn
moves on a straight line, unless the drafting arrangement
and machinery are considerably changed, which is prac-
tically impossible.

It is an object of the invention to provide a simple de-
vice for periodically pulling carded yarn moving through
a drafting arrangement and having a false twist applied
thereto which device can be conveniently mounted on an
existing drafting arrangement without making any ap-
preciable changes. The pulling device according to the
invention includes a stationary yarn guide transversely
intersecting the line extending between the nips of two
drafting roller pairs which define a drafting field. The
stationary yarn guide cooperates with a revolving yarn
guide which is adjacent said stationary yarn guide and
slightly spaced therefrom in the direction of movement
of the yarn and which also transversely intersects the
line extending between the nips of the drafting rollers.
The yarn guides are so arranged that the revolving guide
temporarily diverts the yarn at each revolution of the
revolving yarn guide for producing a pulling effect. The
yarn guides are preferably in the form of rods. The rod
forming the stationary yarn guide is mounted diametrical-
ly on one end of a stationary tubular element which is
coaxial of the yarn in the drafting field. The tubular ele-
ment coaxially rotatably supports an annular element on
which the rod forming the revolving yarn guide is mount-
ed diametrically of the annular element. The latter may
also support false twist producing means, i.e. needles
forming a needle funnel.

The novel features which are considered characteristic
of the invention are set forth with particularity in the
appended claims. The invention itself, however, and
additional objects and advantages thereof will best be
understood from the following description of an embodi-
ment thereof when read in connection with the accom-
panying drawing wherein:

FIG. 1 is a diagrammatic sectional elevation of a draft-
ing arrangement of a carded yarn ring spinning frame.

FIG. 2 is a portion of FIG. 1 on an enlarged scale, 60
particularly showing a false twist element.

FIG. 3 is a large scale plan view of the false twist ele-
ment shown in FIG. 2 and looking in the direction of
the arrow in said figure.

FIGS. 4 to 7 are perspective views of the rods forming
part of the false twist element in different operating posi-
tions.

Referring more particularly to FIG. 1 of the drawing,
numerals 1 and 2 designate two roller pairs defining a
drafting field. A stationary tubular element 4 mounted
on a frame 3 and rotatably supporting a needle funnel
5 which applies a false twist to a fiber compound 6

2

rectilinearly passing through said funnel, is placed be-
tween the roller pairs 1 and 2.

After leaving the drafting arrangement the yarn 6
passes through an eye 7 onto a cop 8. The needle funnel
5 is rotated by a cord 10 laid into an annular groove 9
formed on an annular element or ring 11 to which the
needles forming the funnel 5 are connected. The element
11 revolves on an antifriction bearing 12 whose inner
race is formed by the element 4 whose axis coincides with
the line connecting the nips of the pairs of drafting rollers
1 and 2. A stationary yarn guide in the form of a trans-
verse rod 14 is attached to stationary tubular element 4
and extends diametrically through the bore of the tubular
element at one end thereof and is normal to the yarn
passing through the element 4. The element 11 does not
only support the needles forming the funnel 5 but also
supports a yarn guide in the form of a transverse rod
15 extending diametrically with respect to the ring 11 and
adjacent the rod 14. The rod 15, however, is slightly
spaced from the rod 14 to afford easy passage of the yarn
6 between the rods when the latter are parallel with one
another as shown in FIG. 6.

Plucking or pulling of the yarn is effected as follows:

The yarn may be introduced, for example, at the right
25 side of the rod 14, which is stationary, and is in the position
I indicated in FIG. 3 while the rods 14 and 15 are
parallel. The yarn remains on the right side of the rod
14 in FIG. 3. The rod 15 rotating in the direction of the
arrow shown in FIG. 3 pushes the yarn alongside the rod
30 14 into the position II shown in FIG. 3. This pushing
effect discontinues because the force component which
is parallel with the stationary rod 14 becomes too small
35 to overcome the frictional resistance when the angle α
formed by the rods and shown in FIG. 5 decreases.
Therefore, at continued rotation of the rod 15 toward
the subsequent parallel position of the rods the yarn
40 6 assumes the configuration shown in FIG. 6, i.e., the
yarn is diverted to the left (position III in FIG. 3) by a
distance amounting to about the thickness of the rod 14.
Continued rotation of the rod 15 causes movement of
45 the yarn into the position IV shown in FIG. 3 where the
yarn is released (FIG. 7) and snaps back into the initial
position I to be pushed once more by the rod 15 along the
stationary rod 14 for effecting a new pulling action. Since
the needle funnel makes about 2000 to 3000 revolutions
per minute, the yarn is subjected to an equal number of
pulls while passing through the drafting arrangement.

I claim:

1. A pulling device for periodically pulling carded
yarn passing through a drafting arrangement, comprising:
  - a stationary yarn guide placed in the drafting arrange-
ment transversely to the direction of movement of
the yarn and engaging with the yarn, and
  - 55 a revolving guide placed in the drafting arrangement
transversely to the direction of movement of the yarn
adjacent said stationary guide and forming a clear-
ance therewith permitting passage of the yarn be-
tween said guides, said revolving guide engaging with
the yarn for temporarily pushing the yarn alongside
said stationary yarn guide and pulling the yarn at
each revolution of the revolving yarn guide.
2. A pulling device as defined in claim 1 wherein said
yarn guides are in the form of rods placed in parallel
planes normal to the travel direction of the yarn, the
rod forming the revolving yarn guide rotating around an
axis extending through the longitudinal centers of said
rods and normal to the said rods.
3. A pulling device according to claim 2 comprising
a stationary tubular element placed in the drafting ar-
rangement coaxially of the yarn passing through the

drafting arrangement, said rod forming the stationary yarn guide being mounted on said tubular element, and an annular element coaxially rotatably supported by said tubular element, said rod forming the revolving yarn guide being mounted on said annular element.

4. A pulling device according to claim 3 comprising false twist means mounted on said annular element for applying a false twist to the yarn passing through the drafting arrangement.
